CLOTHES TONGS

Perry M. Peterson, Moline, Ill.

Application April 25, 1945, Serial No. 590,140

1 Claim. (Cl. 294—8.5)

The present invention relates to new and useful improvements in clothes tongs of a type adapted for use in lifting or removing clothes from washing machines, tubs and the like, whereby to avoid burning or injury to the operator's hands and enabling the placing of the clothes into a wringer or the like without the necessity of the operator touching the garment.

As heretofore practiced, the lifting by hand of clothes or other articles out of the water in a washing machine or tub upon completion of the wash is an unpleasant task for many reasons, including the immersion of the hands in the dirty, hot or scalding water, as well as possible injury by pins or other sharp articles, and the danger of injury to the fingers of the operator by getting them caught between wringer rolls when inserting the garments into the wringer.

It is accordingly an object of the present invention to provide lifting tongs for carrying out this portion of the duties of a laundress, and to provide a clothes tongs of simple and practical construction, which is strong and durable, efficient and reliable in use, and otherwise well adapted for the purposes for which the same is intended.

Other objects and advantages reside in the details of construction and operation as more fully hereinafter described and claimed, reference being had to the accompanying drawing forming part hereof, wherein like reference numerals refer to like parts throughout, and in which:

Figure 1 is a side elevational view,

Figure 2 is an edge elevational view,

Figures 3 and 4 are transverse sectional views taken respectively on the lines 3—3 and 4—4 of Figure 1, and

Figure 5 is a group view in elevation of the jaws of the tongs showing the protuberances on the proposed faces thereof for gripping the garments.

Referring now to the drawing in detail, wherein, for the purpose of illustration, I have disclosed a preferred embodiment of the invention, the numerals 5 and 6 designate a pair of elongated arms preferably constructed of wood or other light-weight material, the arms being connected adjacent one end by means of a pair of plates 7 secured at the opposite side of the arm 5 by means of a pair of screws or the like 8 and secured at the opposite sides of the arm 6 by means of a single screw, or the like, 9 which forms a pivot for the arms.

The other ends of the arms constitute gripping jaws and are yieldably maintained in open position by means of a coil spring 10 having its ends recessed in the opposed faces of the arms adjacent the connecting plates 7.

The outer surfaces of the arms adjacent their pivoted ends are rounded, as indicated at 11, to provide a smooth, hand-gripping portion for the

arms, and by means of which the jaws at the free ends of the arms may be closed for gripping and lifting the garments.

The opposed faces of the arms, at the free ends thereof, are provided with headed tacks, nails, or the like, as indicated at 12, the heads of the tacks preferably being constructed of substantially hard rubber and one of the arms is provided with a single tack, as indicated at 13 in Figure 5 of the drawing, while the other arm is provided with a pair of spaced apart tacks, as indicated at 14, and arranged so that the single tack 13 will engage the pair of tacks 14 in substantially triangular formation, thus to provide positive gripping engagement with the garment.

The pivoted ends of the arms 5 and 6 are also provided with openings 15 by means of which the device may be hung from a nail or the like when not in use.

In the operation of the device, since the expansion coil spring 10 yieldingly maintains the free ends of the arms in open position, the clothes or other articles may enter between the free ends of the arms, and upon closing the arms by the hand of a person gripping the rounded portions 11 thereof, the garment will be firmly gripped for lifting the same from a washing machine, tub, or the like, and may thus be placed in a wringer. The headed tacks or nails 12 will prevent slipping of the garment from the jaws formed by the free ends of the tongs.

In view of the foregoing description taken in conjunction with the accompanying drawing, it is believed that a clear understanding of the construction, operation and advantages of the device will be quite apparent to those skilled in this art. A more detailed description is accordingly deemed unnecessary.

It is to be understood, however, that even though I have herein shown and described a preferred embodiment of my invention that the same is susceptible to certain changes fully comprehended by the spirit of the invention as herein described and the scope of the appended claim.

Having thus described the invention, what I claim is:

A clothes tongs comprising a pair of elongated arms, means pivotally connecting the arms to each other adjacent one end, spring means yieldably separating the free ends of the tongs, a single gripping member projecting from the opposed face of one of the arms at the free end thereof, and a pair of gripping members projecting from the opposed face at the free end of the other of said arms, said finger-gripping member being moved into contacting engagement with said pair of gripping members upon closing of the arms.

PERRY M. PETERSON.
